DRAPERY PLEATER HOOK

Sidney Schwartz, Detroit, Mich.

Application December 7, 1956, Serial No. 44,112

Term of patent 7 years

(Cl. D17—12)

Fig. 1 is a perspective view of a drapery pleater hook embodying my new design.

Fig. 2 is a front elevational view thereof.

Fig. 3 is a side elevational view thereof.

Fig. 4 is a rear elevational view thereof.

Fig. 5 is a top plan view thereof.

I claim:

The ornamental design for a drapery pleater hook substantially as shown.
